UNITED STATES PATENT OFFICE

CHARLES L. MANDELERT, OF CHIPPEWA FALLS, WISCONSIN

HUNTING COAT WITH DETACHABLE POCKET

Application filed May 2, 1931. Serial No. 534,485.

The present invention relates to a hunting jacket having a game pocket removably secured to the outer rear portion thereof.

In hunting wild fowl and small game, a hunting jacket having a game pocket therein is an almost essential adjunct to the enjoyment of the sport. However, the hunting seasons occupy but a small portion of the entire year and it is usually the case that after the hunting season is over, the hunting jacket is put away and is of no further service throughout the year. Various types of hunting jackets with removable inner pockets have been made wherein the game pocket is removably secured to the interior of the garment, but in these constructions it is necessary to have game openings in the sides of the jacket, and this, of course, disfigures the jacket for use other than for hunting.

An object of the present invention is to make an improved hunting jacket with a removable game pocket.

The further object is to make a hunting

The further object is to make a hunting jacket having a game pocket thereon which may be disconnected from the jacket at its upper edge and permitted to swing below the lower edge of the rear portion of the jacket to form a seat pad for the wearer of the jacket.

30 These and other features of the invention will be more fully brought forth in the following description and the accompanying drawings, wherein:

Figure 1 is a rear view of the jacket embodying the present invention.

Figure 2 is a vertical, sectional view through the center of the rear portion of the jacket shown in Figure 1.

Figure 3 is a fragmentary view of the lower rear portion of the jacket showing the game pocket in position thereon with the securing means for the top edge of the game pocket partially disconnected.

Figure 4 is a fragmentary view of the upper portion of a removable game pocket having

ing a modified form of fastening means there-on.

Figure 5 is a view in elevation of the rear or outer face of the removable game pocket, one of a pair of end closure means thereon being shown in an opened position, and that in the other end being shown in a closed position. 50

Figure 6 is a view in elevation showing the front or inner face of the removable pocket shown in Figure 5. 55

Figure 7 is a view in perspective of the game pocket showing a preferred bellows construction thereof; and

Figure 8 is a sectional view similar to Figure 2 showing the game pocket released along its upper edge and sides from the jacket and depending below the lower rear edge of the jacket to form a seat pad. 60

Referring to the drawings in detail, a jacket 65 A may be of any suitable type of general construction, except that it is preferably constructed with a flap 1 transversely across the rear portion thereof which may be formed of a fold of the fabric of which the coat is made, as illustrated in Figures 2 and 8. Beneath this flap 1 is secured one half 2 of a hookless fastener, of the type wherein complete separation of the two halves of the fastener is permitted. This type of hookless fastener is well known to the art and it is believed unnecessary to describe it in detail in the present description. A removable

in the present description. A removable game pocket B is constructed with an inner panel 3 having a strip 4 secured across its lower edge and the two sides thereof. To the outer edge of this strip is secured a back panel 5. This construction forms a bellows pocket which is desirable as it gives increased carrying capacity, although the type of pocket is, of course, not material to the invention. A pair of vertical openings 6 and 7 is provided on the two sides of the pocket B and the edges of these openings are provided with hookless fasteners 8 and 9, respectively.

- ly, which facilitate the opening and closing of these openings. Snap fasteners 10 are preferably provided along the side portions and across the bottom of the pocket and are positioned to engage co-operating snap fasteners 11 positioned on the rear of the jacket to hold the pocket securely in place. Instead of the separable hookless fastener provided across the upper edge of the game pocket B a plurality of snap fasteners may be provided beneath the flap 1 on the jacket and across the upper edge of the game pocket to removably secure the pocket to the jacket. The game pocket may be lined with a blood-
proof material, if desired, as is common practice in the better grades of hunting jackets, but as this practice is well known to the art, it is believed unnecessary to complicate the drawings by showing this feature.
- 20 Frequently, in the shooting of wild fowl, such as ducks, a hunter finds his best shooting in swampy ground, or on a rainy day when the seats of the duck boat or blind are wet. The game pockets are not ordinarily used in this type of shooting, since the hunter usually stays in one spot and waits for the ducks to come over him, and, therefore, the only time the pocket is used is in carrying the game in from the shooting grounds to the camp.
- 25 For this type of shooting the upper and side edges of the pocket may be released from the jacket, leaving the pocket secured only at its lower edge and the pocket may be permitted to hang downwardly below the lower edge of the jacket, as shown in Figure 8. In this position the pocket forms a water-proof seat pad, the utility of which will be immediately apparent to wild fowl hunters.
- 30 The removable feature of the pocket will also be appreciated by upland game hunters, since in working back and forth across a field, it will become necessary to carry the game pocket after a few birds have been bagged, and in working back and forth across the field the game pocket may be left at one end of the field and the birds placed therein upon the completion of each circuit of the field.
- 35 The pocket provides a convenient receptacle for extra shells and other items when going to and from the hunting grounds, and when the pocket is removed the jacket may be used for ordinary outing wear. The flap 1 conceals the top pocket fastening means and with the exception of the fasteners 11 which are not conspicuous, there is nothing to indicate that it is a hunting jacket.
- 40 I claim:
1. A hunting and outing jacket, comprising a jacket, a pocket removably secured to the outer rear portion thereof, the upper edge of said pocket being removable from engagement with said jacket to permit the said
- 45 pocket to hang below the lower rear portion of said jacket to form a seat pad.
- 50 2. A hunting and outing jacket, comprising a jacket, a transversely disposed narrow flap on the outer rear portion of said jacket, fastening means mounted beneath said flap to be concealed thereby, and a separate game pocket having fastening means across the upper edge thereof to engage said fastening means beneath said flap to support said pocket.
- 55 In testimony whereof I affix my signature.
